COMBINATION COLD AND HOT PACK

Hugo Gloeckler, Flushing, N. Y.

Application October 17, 1953, Serial No. 21,874

Term of patent 14 years

(Cl. D83—1)

To all whom it may concern:

Be it known that I, Hugo Gloeckler, a citizen of the United States of America, residing at Flushing, county of Queens and State of New York, have invented a new, original, and ornamental Design for a Combination Cold and Hot Pack, of which the following is a specification, reference being had to the accompanying drawing, forming part thereof, in which,

Figure 1 is a rear elevational view of a combination cold and hot pack, embodying my new design;

Figure 2 is a front elevational view thereof with the head straps broken away for convenience of illustration; and

Figure 3 is a view partly in cross section taken on the line 3—3 of Figure 2.

The essential features of my design reside in the portions shown in full lines.

I claim:

The ornamental design for a combination cold and hot pack, as shown and described.

HUGO GLOECKLER.
